UNITED STATES PATENT OFFICE.

WILLIAM H. ROBERTSON, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND.

CASH REGISTER.

Application filed June 7, 1923. Serial No. 643,921.

This invention relates to cash registers, and particularly to improvements in the type of machine shown in Letters Patent of the United States issued to E. J. Von Pein, 5 March 15, 1921, No. 1,371,653.

An object of this invention is the provision of tablet indicators arranged in groups, and selected and moved to a display position by the operation of item entering keys.

With this and incidental objects in view, the invention consists of certain novel features of construction and combinations of parts, the essential elements of which are set forth in appended claims and a preferred form of embodiment of which is hereinafter described with reference to the drawings which accompany and form part of this specification.

Of said drawings:

20 Figs. 1^A and 1^B together constitute a rear elevation of the machine.

Fig. 2 is a detail view of the indicator supporting element and a part of the selecting mechanism.

25 Fig. 3 is a detail view of a part of the indicator selecting mechanism.

Fig. 4 is a detail rear view of the registering segments and gear mechanism for operating the indicator selecting mechanism.

30 Fig. 5 is a sectional view of the machine taken inside the right hand side frame.

Fig. 6 is a detail view of the mechanism for imparting movement to the cam shaft.

35 Fig. 7 is an elevational view of the right hand end of the machine showing the printer and a part of the indicator mechanism.

The embodiment illustrated comprises the usual amount keys, means for entering amounts in a totalizer and for printing the same. In addition, mechanism is provided for indicating both to the front and rear of the machine, the last amount entered.

40 Referring especially to Fig. 5, the invention is shown in connection with the well known lever key type machine. The keys 25 arranged in denominational groups as usual, are pivoted on a transverse rod 26, and at their rear ends are notched to cooperate with a lip on a key coupler 27 to oscillate the key coupler each time a key is operated.

The key coupler 27 is pivoted on trun-

nions 28 having bearings in the side frames of the machines.

Uprights 29, connected to the rear ends 55 of the keys engage rods 30 mounted in rocker members 31, supported on a shaft 32. There is a rocker member for each denominational group of keys 25, and each of the members is operatively connected to its 60 registering segment or totalizer actuator 33. The notches in the uprights 29 are located to transmit amounts of movement to the actuators proportionate to the number of units represented by the keys to which the 65 uprights are connected.

The registering segments 33 are normally in mesh with gears 34 connected to the item type wheels 35 (Fig. 7) by telescopic sleeves 36 (Fig. 5) to print the items on a record 70 strip which will hereinafter be described.

The key coupler 27, before referred to, is pivotally mounted in the side frames and rests upon the rear ends of the keys from which it receives its movement. The right 75 hand end of the key coupler carries a roller 40 (Fig. 6) which engages a rack plate 41 to give a rotation to a shaft 42 (Fig. 5) at each operation of the machine.

Secured to the shaft 42 is a cam 43 which 80 engages rollers on a lever 44 to rock a totalizer 45 into and out of engagement with the totalizer actuator 33 to enter the items registered by the item entering keys 25. This totalizer being of such a well known 85 type, a detailed description of the mechanism will not be given herein.

The totalizer actuator 33 (Figs. 4 and 5) in addition to actuating the totalizer and type printing wheel actuates a tablet indicator selecting device. Each actuating segment 33 is in constant engagement with a pinion 46. These pinions are connected to companion pinions 47 by hubs 48 freely mounted upon a rod 49 supported by the 95 frames of the machine. The companion pinions 47 mesh with segments 50 which are secured to segments 51 in mesh with gear racks 52. The segments are secured to hubs freely mounted upon a rod 53 and laterally 100 spaced by collars 54.

The gear racks 52 are supported at their forward ends by the rod 49 and their rear ends are pivoted on a stud 55 secured in

indicator selecting arms 56 which are freely mounted on a rod 57 and a telescopic sleeve 58 surrounding this rod. The indicator selecting arms are moved to positions corresponding to the item keys depressed in their respective groups.

Cooperating with each indicator selecting arm 56 is an indicator supporting frame consisting of two upright members 63 (Figs. 1^A, 2 and 5) secured at their lower ends on hubs 64. The left hand hub in Fig. 1^A is pinned to the rod 57. The next hub to the right is secured to a sleeve 58 which is freely mounted on the rod 57, and the third hub is freely mounted on the sleeve 58. The upper ends of the upright members are joined by a yoke 65 which also supports the indicator tablets 66 in their normal position. The upper ends of the members 63 are slightly offset and are provided with radial slots 67 uniformly spaced and adapted to receive the indicator tablets.

The indicator supporting members are moved into a position corresponding to the actuated position of the indicator selecting arms 56 by pairs of arms 68 joined together at their upper ends by pins 69 upon which are freely mounted rollers 70 engaging the sides of openings 71 in the members 63. Similar openings 72 in the indicator selecting arms 56 form means for guiding the indicator supporting members to position as the rollers 70 move to the upper part of the openings. The upper portions of the openings 71 and 72 are defined by parallel sides and are of a width to fit the roller 70. Because of this provision, variations in the movement of the roller 70 will not affect its alining function as this function is performed not only when the roller is at its extreme upward position but also as it moves into and out of such position.

The arms 68 are secured at their lower ends on opposite ends of hubs 73 which are freely mounted upon a rod 74 supported at each end by arms 75 which are pinned to a rod 76 supported by the frame of the machine. The rod 76 is rocked at the proper time during the operation of the machine by an arm 80 (Figs. 1^A, 2 and 7) which is pinned to the trunnion 28 of the key coupler 27. Formed in the right hand end of the arm 80 is a cam slot 81 which cooperates with a roller 82 mounted on an arm 83 to rock the shaft 76 near the end of the upward movement of the key coupler. The arm 83 is freely mounted on a stud 84 supported by the frame of the machine and has pivotally connected to the arm a link 85, the upper end of which is pivoted to an arm 86, pinned to the rod 76. As the indicator supporting members are moved into corresponding position with the indicator selecting members, an alining or locking device holds them rigid while one of the indicator

tablets is elevated to a displaying position. This alining or locking means consists of a notched plate 87 (Fig. 5) secured to one side of the indicator tablets supporting member and cooperates with an arm 88 pinned to a rod 89 supported at each end in brackets 79 fastened to the side frames of the machine. Secured to the rod 89 is a downwardly extending arm 90 (Fig. 7) which is held in contact with a lever 91 by a spring 92. This lever is freely mounted on a stud 93 projecting from the side frame of the machine. Carried on the lower end of the lever is a roller 94 which cooperates with a cam 95 pinned to the shaft 42 to rock the arm 88 (Fig. 5) into engagement with the alining plate 87.

After the indicator supporting members are moved into adjusted position, the indicator tablets which correspond to the item keys depressed are raised into displaying position. The means for accomplishing this consists of a horizontal bar 100 (Figs. 1^A and 5), extending across the top of the machine and secured to vertical plates 101 at each end. These plates are guided in their operation by the brackets 79 by having pins 102 and 103 at each end engaging slots 104 formed in the brackets 79.

The horizontal bar 100 is given a reciprocal motion by links 105 connecting the pins 103 with arms 106 which are integral with partial gears 107 freely mounted on studs 108 (Fig. 7) supported in the frames of the machine. These partial gears mesh with segment gears 109 which are pinned on a rod 110 supported in the frames of the machine. The cam slot 81, formed in the arm 80, in addition to oscillating the rod 76 is also a means for oscillating the rod 110. Cooperating with this cam slot is a roller 111 mounted on a pivot stud connecting an arm 112, freely mounted upon the stud 84, with a link 113, the upper end of which is pivotally connected to the segment gear 109. The cam 81 is formed so as to move the horizontal bar 100 downward and place the last indicator tablets displayed in their normal position before the indicator supporting members are moved into their new positions, corresponding to the last item key depressed. After the indicator supporting members assume their new positions the horizontal bar is returned to its upper, or normal, position, displaying the new indication. The lower edge of the horizontal bar 100 (Fig. 1^A) has a plurality of slotted openings 116 through which the tops 117 of the indicator tablets 66 pass as the supporting members are being adjusted. Notches 118 formed on opposite sides of the indicator tablets engage horizontal lugs 119 on the bar 100 to support the indicator tablets in their display position.

The indicators are arranged to be displayed in two groups, one group to be seen from the front of the machine and the other from the rear. The indicator tablets of the 5 center group are provided with characters on both sides to indicate to both front and rear. The indicators of the other groups to the right of the center group are seen only from the rear of the machine, and 10 their supporting members 63 are mounted on hubs 64, one of which is secured to the rod 57 and the other to the sleeve 58, which is the means of moving these two groups of 15 back indicators in unison with corresponding groups of front indicators previously described.

The indicators are displayed through 20 openings in indicator guiding plates 120 supported by the brackets 79. Each item as it is entered in the totalizer and indicated is also printed upon a record strip 125 which is fed from a supply roll 126 over guide pins to a receiving roll 127, the receiving roll being moved counter-clockwise at each 25 operation of the machine by a spring-pressed pawl 128 carried on an arm 129 pinned to the key coupler trunnion 28. A hammer platen 130 operated by a cam on the shaft 42 cooperating with a spring plunger 131 causes a legible impression to be made from 30 the type printing wheel 35 upon the record strip 125. A continuous inking ribbon 132 passes between the record strip and the type wheels and over suitable feeding roller and 35 guide studs. At the time the impression is made the usual alining member 133 engages the type printing wheels. This printing mechanism being of a well known type is but briefly described herein.

40 Operation.

An amount is entered on the totalizer and 45 printed on a detail strip by operating keys representing such amount, these parts of a registration being performed by mechanism well known in the art. As the actuators 33 are moved differentially from the keys to operate the totalizer and adjust the printing wheels, they also operate indicator selecting 50 arms 56 (Fig. 5). At the beginning of the operation previous exposed indicators are lowered by the link 105, etc. (Fig. 7). Toward the end of the downward movement of the keys the lower end of the cam slot 81 (Fig. 7) swings the arm 83 and through the mechanism shown in this figure and in Fig. 5 raises the roller 70 which is guided in slot 72 of the differentially positioned indicator selecting arm 56 (Fig. 3) to position the indicator supporting members 63 (Fig. 2) as 55 determined by said selecting arm. The indicating supporting member is now alined by aliner 88 (Fig. 5) operated by a cam 95 on the revolution shaft 42 (see also Fig. 5).

60 The keys are now fully depressed. The

operator permits them to return to home position. At the end of this movement the upper portion of the cam 81 (Fig. 7) engages the roller 111 and raises the link 105 to lift the selected indicator into view. The 70 other parts of the machine are returned to normal in the usual way. The machine is now ready to receive another registration.

75 While the form of mechanism herein shown and described is admirably adapted to fulfill the objects primarily stated, it is to be understood that it is not intended to confine the invention to the one form of embodiment herein disclosed, for it is susceptible of embodiment in various forms all 80 coming within the scope of the claims which follow.

What is claimed is:

1. In a machine of the class described, the combination of a totalizer, a totalizer actuating means, item entering means adapted to operate said actuating means, a key coupler operated by said item entering means, indicating elements, indicating elements supporting means, indicating elements selecting means, indicating elements supporting means 85 alining means, and means actuated by said key coupler for elevating to a displaying position one or more indicating elements.

2. In a machine of the class described, the combination of item entering means, a rocking member actuated by said item entering means, indicating elements, indicating elements supporting means adapted to be differentially moved, indicating elements selecting means, indicating elements elevating means, and means actuated by said rocking member to move said indicating elements supporting means to a position corresponding to the position of said indicating elements 100 selecting means.

3. In a machine of the class described, the combination of item entering means, a rocking member actuated by said item entering means, a pivoted member adapted to be 105 moved differentially by said item entering means, indicating elements, indicating elements supporting means, a movable member actuated by said pivoted member for controlling the adjustment of said supporting means, indicating elements lifting means, and means operated by said rocking member for actuating said indicating elements supporting means and said indicating elements lifting means.

4. In a machine of the class described, the combination of item entering means, a key coupler, a pivoted member adapted to be differentially moved by said item entering means, indicating elements, a movable means supporting said indicating elements, a movable member actuated by said pivoted member for controlling the adjustment of said supporting means, indicating elements lifting means, and means adapted to move with 125 130

said key coupler for alternately operating said indicating elements supporting means and said indicating elements lifting means.

5. In a machine of the class described, the combination of item entering keys, an actuating segment differentially moved by said item entering keys, a rocking member operated by said item entering keys, indicating elements, a movable member for supporting 10 said indicating elements, a second movable member adapted to be moved differentially by said actuating segment, a rack pivoted to said second movable member, gears intermediate said rack and said actuating segment 15 adapted to transmit motion from said actuating segment to said rack, and means operated by said rocking member and cooperating with said second movable member to differentially position said indicating elements supporting member.

6. In a machine of the class described, the combination of a totalizer, a totalizer actuator, item entering keys, a rocking member operated by said item entering keys, 25 a movable indicator supporting member adapted to support a plurality of indicators in normal position, means intermediate said totalizer actuator and said indicator supporting member adapted to adjust said indicator supporting member from the totalizer actuator, and means actuated by said rocking member for removing one of said indicators for the purpose of display.

7. In a machine of the class described, the combination of a totalizer, actuating means therefor, item entering means, means intermediate of the item entering means and the actuating means for differentially moving said actuating means, a rocking member operated by said item entering means, indicating elements, a pivoted member supporting said indicating elements, a second pivoted member operated by said actuating means, means operated by said rocking member and 45 cooperating with said second pivoted member for adjusting said first pivoted member, and means operated by said rocking member for moving one of said indicating elements into indicating position.

8. In a machine of the class described, the combination of a totalizer, a totalizer actuating means, an item entering means adapted to operate said actuating means, a rocking member operated by said item entering means, indicating elements, a movable means supporting said indicating elements, a second movable means operated by said actuating means, and means operated by said rocking member for moving said indicating elements supporting means to a corresponding position with said second movable means.

9. In a machine comprising lever keys, a key coupler, a totalizer, totalizer actuating 65 segment gear, differential connections be-

tween the keys and actuating segment gear, the combination of indicating elements, indicating elements supporting means, indicating elements selecting means, and means intermediate the key coupler and the indicating elements selecting means for moving said indicating elements supporting means to a position corresponding to the position of said indicating elements selecting means.

10. In a machine comprising lever keys, 75 a key coupler, a totalizer, totalizer actuating segment gear, differential connections between the keys and actuating segment gear, the combination of indicating elements, indicating elements supporting means, indicating elements selecting means, and means actuated by said key coupler for elevating to a displaying position one of said indicating elements.

11. In a machine comprising lever keys, 85 a key coupler, a totalizer, totalizer actuating segment gear, connections intermediate the keys and actuating segment gear, the combination of indicating elements, indicating elements supporting means, indicating elements selecting means, and means cooperating with said key coupler for raising and lowering one of said indicating elements.

12. The combination of an adjustable tablet indicator supporting carriage, tablets carried thereby, a plurality of keys, a key coupler, slotted means operated by said key coupler, means cooperating with one end of the slot of said slotted means for moving the carriage to a position determined by the key depressed, and means cooperating with the other end of the slot for moving said tablets to indicating and home positions.

13. In a machine of the class described, the combination of item entering means, an actuating means, an oscillating member actuated by said item entering means, indicating elements, a movable means supporting said indicating elements, a second movable means 100 operated by said actuating means, means operated by said oscillating member and directly cooperating with said first and second movable means for moving said first movable means to a position corresponding 110 to that of said second movable means, and means for locking said indicating elements supporting means after it is moved into said position.

14. In a machine of the class described, 120 the combination of item entering means involving a differentially movable actuator, an oscillating member actuated by said item entering means, indicating elements supporting means adapted to be differentially moved, a driving means operated by said item entering means, an indicator selecting member differentially positioned by said actuator, means actuated by said oscillating member and cooperating with said indicator select- 125 130

ing member to position said indicating elements supporting means, and means operated by said driving means for locking said indicating elements supporting means in position.

15. In a machine of the class described, the combination of item entering means, an actuating segment gear, an indicating element supporting member, an indicating ele-

ment selecting member, a rod pivotally supporting said members, a gear rack pivoted to said selecting member, gear means intermediate of said actuating segment gear and said gear rack, and means for alining said indicating elements supporting means. 10 15

In testimony whereof I affix my signature.

WILLIAM H. ROBERTSON.
